UNITED STATES PATENT OFFICE

106,479

DESIGN FOR A PLATE OR SIMILAR ARTICLE

Alexander Crane, Cheshire, Conn.

Application February 11, 1937, Serial No. 67,596

Term of patent 7 years

To all whom it may concern:

Be it known that I, Alexander Crane, a citizen of the United States, residing at Cheshire, in the county of New Haven and State of Connecticut, have invented a new, original, and ornamental Design for a Plate or Similar Article, of which the following is a specification, reference being had to the accompanying drawing, forming part thereof.

The figure is a top plan view showing my new design.

The contour of the plate and the depth of the bowl portion are conventional.

I claim:

The ornamental design for a plate or similar article, as shown and described.

ALEXANDER CRANE.
